VENDING MACHINE

Stanley James Horsch and Lowell Otis Hole,
Detroit, Mich.

Application May 4, 1950, Serial No. 159,884

1 Claim. (Cl. 312—69)

1 This invention relates to a vending machine and more particularly to a coin controlled dispensing machine wherein articles of merchandise are adapted to be placed in hotels, railway cars, stations or other public places for mechanical merchandising packages or the like.

The invention has for its object the provision of a machine of the class stated which is of simple and inexpensive construction and positive in its function of vending the articles contained therein.

Another object of the invention is to provide mechanism which will receive a coin and position the coin between movable parts whereby the coin serves as a key for manipulating the discharge mechanism of the machine.

A further object of the invention is to provide a closure member for the coin insert slot which is positioned by the articles in the machine so that when all of the articles have been removed from the machine, the closure member is positioned over the coin insert slot.

With the above and other objects in view, the invention further resides in novel details of construction, combination and arrangement of parts hereinafter more fully described, reference being had to the accompanying drawings, in which:

Fig. 1 is a front elevational view of the machine with the front cover removed;

Fig. 2 is a perspective view of the machine;

Fig. 3 is a side elevational view of the mechanism in the machine, the housing and operating shaft being shown in section;

Fig. 4 is a sectional view taken on line 4—4 of Fig. 1; and

Fig. 5 is an enlarged sectional view taken on line 5—5 of Fig. 1.

Referring to the drawings, the housing 10 comprises a back plate 12 having vertical side walls 14 and a removable front wall 16. The back wall 12 is provided with oppositely disposed angle plates 18 which form a vertically extending channel which receives the articles of merchandise in stacked formation.

An inverted U-shaped bracket 20 is secured to the back wall 12 through lateral flanges 22 on the legs 24 of the U-shaped bracket 20. The base of the U-shaped bracket 20 forms a floor or support for the articles to be dispensed.

The legs 24 of the bracket 20 are provided with aligned openings for rotatably supporting a transversely extending shaft 26. A sleeve 28 rotatably mounted on the shaft 26 also extends through the aligned openings in the legs 24 and both are rotatable in the openings. Arms 30 and 32 car-

2 ried on the sleeve 28 at its opposite ends and at the outer side of the legs 24 pivotally support a U-shaped rod 34 which rests on the floor of the bracket 20 and at the rear of the bottom article in the machine.

One arm 32 is provided with a laterally disposed flange 36 having its outer edge formed semi-circular as shown at 38.

Mounted on the shaft 26 is an arm 40 which is spaced from the arm 32 and has a laterally extending flange 42 having a semi-circular edge 44 mating with the semi-circular edge 38 on the arm 34. The flanges 36 and 42 are in horizontal alignment and the semi-circular edges form an annular opening for the reception of a coin. The arm 32 being carried by the sleeve 28 is independently movable relative to the arm 40 which is fixed to the shaft 26, except when a coin is positioned in the opening formed by the semi-circular edges 38 and 44.

The shaft 26 extends through the housing at one side thereof and is provided with a handle 46 for turning the shaft 26. By rotating the handle 46 the shaft 26 rotates in the sleeve 28 and the arm 40 moves with the shaft, but when no coin is in the opening the arms 32 and 30 are stationary so that the delivery arm 34 is not moved.

A coin slot 48 is provided in the front wall 16 and chute 50 is carried by a bracket 52 secured to the back plate 12. This chute directs the coins, through extension 54, to the opening between the semi-circular edges 38 and 44. Directly below the flanges 36 and 42 is a laterally extending flange 56 carried by the arm 40 which guides a piston having a head 58 and a stem 60. The head 58 normally is positioned below the coin opening formed by the flanges 36 and 42 and is adapted to pass therethrough. A flange 62 is formed on the piston stem 60 and a spring 64, surrounding the stem, is under compression between the flanges 56 and 62. The outer end of the piston stem 60 rides on a cam track 66 formed in a bracket 68 secured to the back plate 12.

The cam 66 is designed to move the piston head 58 upwardly into the coin opening when the arms 32 and 40 are pivoted forwardly by turning the shaft 26. At the end of the cam 66 there is a stop 70 which limits the travel of the arms.

When a coin is in the coin opening, between the two flanges 36 and 42 and rests on the piston head 58, the coin forms a key which locks both arms 32 and 40 causing rotation of the sleeve 28, forward movement of the arms 30 and 32, and forward movement of the delivery arm 34 along

the floor of the bracket 20. As the piston stem 60 moves forwardly and upwardly along the track, the piston head 58 pushes the coin upwardly out of the coin opening and it is discharged to the coin receptacle 72 freeing the connection between the arms 32 and 40.

A pin 74 secured to the shaft 26 passes through a slot 76 in the sleeve 28 and has a tension spring 78 between the pin 74 and the back plate 12 urging the shaft 26 in a clockwise direction. While the pin 74 has lost play movement in the slot 76 it does engage the ends of the slot to cause rotation of the sleeve 28 with the shaft 26 and limits its free movement. Thus the spring 78 returns the shaft 26 and sleeve 28 to their normal positions and after a predetermined turning of the shaft 26, the pin 74 turns the sleeve 28.

The coin opening in the flanges 36 and 42 is of a diameter no larger than the diameter of the coin to be used in the machine so that larger coins will not rest on the piston head 58 and serve as a key for interlocking the arms 32 and 40. An opening 88, having a diameter less than the diameter of the required coin diameter is provided in the bottom wall of the chute 50 so that coins, smaller in diameter than those required to accurately fit the coin opening between the flanges 36 and 42, will drop through the opening 88 and pass through a coin return chute 82 into a coin receptacle 84, arranged on the front cover, at the operator's disposal.

A permanent magnet 86 is arranged in the coin chute 50 to intercept and retain coins not of the proper metallic content.

A plate 88, floating on the top of the upper article in the machine, carries a hinged plate 90 at its forward edge. The plate 90 extends rearwardly and has a projection 92 extending laterally beyond the edge of the stacked articles. The forward edge of one of the angle plates 18 is formed tapered at 94, as shown in Fig. 3, and the extension 92 is guided, by the tapered surface, to a vertical position as the stack of articles is diminished. When the last articles have been removed from the machine the extension 92 covers the coin insert slot 48, thereby preventing the operator from inserting a coin in an empty machine. The extension 92 can not be pushed rearwardly due to the fact that it is backed up by the tapered edge 94.

The front wall 16 is removable and is held in closed position by a key lock 96 of conventional design. The article discharge opening is shown at 98 and is normally closed at the rear by a swinging plate 100. When the articles are discharged, the plate 100 is free to swing forwardly and upwardly, permitting the article to be pushed through by forward movement of the arm 34. The plate 100 is prevented from swinging rearwardly and upwardly by its contact with the articles in the machine. This arrangement prevents the operator from reaching through the discharge opening to remove the bottom article.

The discharge opening 98 is formed in a casing 102 which has a window 104 for containing and displaying one of the articles which corresponds to the articles in the machine. The panel 106 may be decorative, such as a mirror, or display advertising material.

The machine is filled by removing the front wall 16 and placing the articles in stacked form on the floor 20 in front of the arm 34. The plate

88 is then placed on the upper article of the stack with the extension resting against the tapered edge 94.

In operation, the operator inserts the proper coin in the slot 48. The coin falls through the chute 50 and if large enough to pass the opening 80 it passes through the extension chute 54. If the coin is not too large it positions itself in the coin opening between the flanges 36 and 42, resting on the piston head 58. The operator then turns the shaft 26 which turns the arm 40 forwardly and the coin, acting as a key, carries the arm 32 forwardly rotating the sleeve 28. The arms 32 and 30 draw the discharge rod 34 forwardly moving the bottom article through the discharge opening 98. When the operator releases the torque on the shaft 26, the spring 78 returns the shaft to its normal position and the pin, acting against the end of the slot 76, returns the sleeve to its normal position with the discharge rod 34 positioned behind the next article.

While we have illustrated and described a preferred embodiment of the invention, it will be understood that various changes, including the size, shape and arrangement of parts, may be made without departing from the spirit of our invention and it is not our intention to limit its scope other than by the terms of the appended claim.

We claim:

A vending machine comprising a housing having an article supporting floor, a pair of vertically extending angle members forming a channel above said floor for positioning the articles one above another on the floor, coin controlled mechanism operable in conjunction with manually controlled means for dispensing the bottom article through an opening in said housing, a coin receiving slot in said housing, the forward edge of one of said vertically extending angle members being tapered forwardly and downwardly, a floating plate resting on the top article in the channel, and a plate hinged to the forward edge of said floating plate and having its rear edge resting on the tapered edge of said angle member, said hinged plate slidably mounted along the tapered surface of said angle members when said floating plate is moved downwardly whereby it is hinged forwardly during downward travel along the tapered surface and covers said coin receiving slot when said floating plate reaches said floor.

STANLEY JAMES HORSCH.
LOWELL OTIS HOLE.
